TUBE ROLLING MACHINE

Andrew Szabo, Jr., Lorain, Ohio

Application December 19, 1941, Serial No. 423,606

2 Claims. (Cl. 80—13)

My invention relates to an improved method for the manufacture of seamless or weldless steel tubes and relates further to improved mechanism used in the said method.

It is an object of my invention to provide an improved method for manufacturing seamless or weldless steel tubes by means of a minimum number of operations and in a highly efficient and economical manner.

Another object of my invention is to provide an improved method for manufacturing seamless or weldless steel tubes wherein the tube when it is passed through a piercing operation has uniform pressure exerted thereon whereby said tube when it leaves the piercing mechanism has a wall of substantially uniform thickness throughout.

Another object of my invention is to provide an improved method for manufacturing seamless or weldless steel tubes in which the piercing and rolling mill operation may be concurrently effected.

Another object of my invention is to provide an improved method for manufacturing seamless or weldless steel tubes in which the reeling operation may be eliminated, if desired.

Another object of my invention is to more efficiently produce a seamless steel tube having a uniform wall of the desired thickness throughout.

Another object of my invention is to provide an improved method for straightening steel tubes.

Another object of my invention is to provide an improved method for straightening steel tubes according to a cold process.

Further objects of my invention and the invention itself will become more readily apparent by reference to the specification hereof and the drawings, in which drawings:

Fig. 1 is a front elevational view partially in section showing the improved piercing and rolling mill machine of my invention;

Fig. 2 is a sectional view taken on the plane from the line 2—2 of Fig. 1;

Fig. 3 is a sectional view taken on the plane from the line 3—3 of Fig. 1; and

Fig. 4 is a top elevational view of the piercing and rolling machine of my invention.

Referring to the drawings, as illustrated in Fig. 1, the seamless tube forming machine of my invention, according to a preferred embodiment thereof, comprises a piercing machine 1 and a rolling machine 2, the operation of said piercing and rolling machine being concurrently operating, said tube forming machine comprising

5 ing a relatively large roller 3 which is centrally positioned in the base of a mill housing 20, said roller being mounted in a suitable bearing block 10 disposed in said housing.

A relatively smaller roller 4 is mounted in the preferred embodiment of my invention shown in Fig. 1 directly above the larger roller 3 and spaced therefrom, said relatively smaller roller 4 being mounted in said housing 20 by means of a bearing block 12. At either side of said rollers 3 and 4 and spaced therefrom a pair of rollers 5 and 6 are disposed, said rollers being mounted in bearing blocks 11 and 13 in said housing and being of preferably the same dimensions as said roller 4, the side rollers 5 and 6 being preferably inclined at an angle to the center rollers 3 and 4 and spirally arranged with respect to the axis of the billet to be passed through the pass x in the piercing machine and the resultant tube through the pass y in the rolling machine, said tube being in the form of a solid round billet when introduced into the piercing machine and a seamless tube when introduced into the rolling machine after having been pierced.

It is to be understood however that any preferred mounting of the plurality of rollers employed in my invention could be utilized, this according to any well known practice of mounting such machines, for example, it can be easily understood that the illustrated mounting could be reversed and the larger roller 3 mounted in the position shown for the roller 4, the rollers 4, 5 and 6 then being disposed generally in the base and center of the mill housing; other arrangements might also be made.

The rollers 3 and 4 are further disposed at an angle to the rollers 5 and 6 and spirally arranged with reference to the billet and the tube, hence the billet after being heated to a high forging temperature and then introduced between the relatively heavy rolls 3, 5 and 4, the same being disposed at an angle thereto is grasped by the revolving rolls 3, 5 and 4, rapidly revolved and pulled slowly forward as shown further in Figs. 2 and 4 while at the same time the metal is drawn away from the center to form a hole within said billet, the metal flowing over and about the mandrel 8 thus forming a tube 9.

50 After leaving the pass x, the billet is placed in the pass y between the rolls 4, 6 and 3, to have a further rolling operation performed thereon whereby the tube is elongated and rolled to smooth the outer surface, said rolling being accomplished over a mandrel 14 which supports the

walls of the tube whereby the tube is reduced in thickness to the gauge desired and proportionately lengthened, the tube achieving a uniform wall of the desired thickness throughout and being substantially of perfect cylindrical form.

It is to be noted that the degree of inclination at which the rolls are inclined with respect to the billet and the tube in the piercing and rolling operations respectively may be varied whereby the speed with which the billet will be drawn through the mill can be shortened within certain predetermined practical limits, according to the particular requirements of the job and the size billet to be processed. It is to be noted that in both the piercing and rolling operations, a three point contact is had by means of the particular three rolls associated therewith and that hence the force exerted on said billet and the resultant tube is uniformly distributed to revolve the billet and tube.

It is further to be noted that while one billet is being pierced in the work pass *x*, which is proceeding in the direction illustrated therefor in Fig. 4, that an already pierced tube is being rolled in the reverse direction, as illustrated in Fig. 4, through the work pass *y* and that the rolls 3 and 4, as above stated, operate concurrently on work pieces in the work passes *x* and *y*.

It is understood that within the purview of my invention that the work passes *x* and *y* may similarly be utilized for other operations on steel tubes or cylindrical work pieces of that type, for example a tube may be pierced in the work pass *x* and rolled in the work pass *y*; also, the improved integral two-pass machine of my invention may be utilized for straightening tubes according to well known cold processes as well as for drawing and rolling.

Hence it can be seen that rolls 3 and 4 operate concurrently in both the piercing and rolling machines accomplishing a duality of purpose and also the speed of rotation of the roll 3 may be suitably varied and shortened with respect to the speed of rotation of the relatively smaller rolls 5, 4 and 6. The preferred shape of said rolls is however that shown in Fig. 4 wherein the same are illustrated as being generally cone shape, the surfaces composed of frustums of two cones, the center lines thereof exerting pressure concentrically about the billet and the resultant tube.

As illustrated in Fig. 4, upon the billet being removed from the piercing machine, it is speedily and easily transferred into the rolling machine, the time element required for the operation being extremely small and much less time than formerly was consumed in taking a billet after it had been pierced out of a piercing ma-

chine and transporting it to a different machine located elsewhere with the improved result in the present instance of effecting a much finer machining of the tube since the heat of the billet is only diminished a slight amount and no deleterious cooling of the tube occurs which causes flaking or graining.

Also, it is to be understood that although I have shown but one embodiment of my invention that numerous and extensive departures may be made therefrom without departing however from the spirit of my invention as set forth in the appended claims.

I claim:

1. In a seamless tube forming machine, a plurality of rolls, two of said rolls being disposed in centered relation to said other rolls, said other rolls disposed laterally thereof, a pair of working passes being formed between said center rolls and said laterally disposed rolls, each of said laterally disposed rolls being inclined at an angle to each of said center rolls and spirally disposed with respect to the axis of the work passes and of work pieces passing therethrough, each of said center rolls and one of said laterally disposed rolls adapted to engage a work piece passing through each separate work pass, said center rolls being simultaneously concurrently engaged in processing the two work pieces in the separate passes, one of said center rolls being relatively larger than said other rolls and adapted to exert rotating force on each of said work pieces, the speed of rotation of said larger center roll being relatively proportioned with respect to the speed of rotation of said other rolls, the said center roll being adapted to assist in exerting equal force upon each of the work pieces and to propel the same in opposite directions.

2. In a seamless tube forming machine, a plurality of rolls, two of said rolls being disposed in centered relation to said other rolls, said other rolls disposed laterally thereof, a pair of working passes being formed between said center rolls and said laterally disposed rolls, each of said laterally disposed rolls being inclined at an angle to each of said center rolls and spirally disposed with respect to the axis of the work passes and of the work pieces passing therethrough, each of said center rolls and one of said laterally disposed rolls adapted to engage a work piece passing through each separate work pass, said center rolls being simultaneously concurrently engaged in processing the two work pieces in the separate passes and propelling said work pieces in opposite longitudinal reciprocal relation to each other, said work pieces being in spaced parallel planes.

ANDREW SZABO, JR.
